UNITED STATES PATENT OFFICE.

JOHN A. MCINTYRE, OF DENVER, COLORADO.

INTERNAL-COMBUSTION PRESSURE-PUMP.

1,171,620.

Specification of Letters Patent. Patented Feb. 15, 1916.

Application filed November 27, 1914. Serial No. 874,111.

To all whom it may concern:

Be it known that I, JOHN A. MCINTYRE, a citizen of the the United States, residing in the city and county of Denver and State of Colorado, have invented certain new and useful Improvements in Internal-Combustion Pressure-Pumps; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in internal combustion pumps, or constructions which are adapted to raise water through the instrumentality of the pressure generated by explosions, the force of which is delivered to the water to be raised in such a manner that the latter is advantageously lifted in a continuous stream.

My improvement comprises a double cylindrical construction in each member of which the explosions take place and are properly timed in alternate relation.

In my improved construction, the charge of explosive mixture is drawn into one extremity of either cylinder as the piston therein is moved toward the opposite extremity as the result of a partial vacuum produced on the opposite side of the piston of the other cylinder, due to the combustion, whereby the oxygen of the air has been consumed. In other words, every time an explosion takes place in one piston chamber, the force of the explosion acts to open an outwardly opening check valve with which the piston is provided, the said check valve normally closing ports in the piston. The force of this explosion after opening the check valve, passes through a conduit to the surface of the water from which the supply is to be taken. The partial vacuum produced by the explosion serves to return the piston in the cylinder where the last explosion took place, to the opposite end of the cylinder from that which it occupied at the time of the explosion. This last named movement of the piston in one cylinder imparts an outward movement to the piston of the other cylinder, due to the fact that the two cylinders are connected by the same piston stem. The said outward movement just stated results in drawing a charge of explosive

mixture into the cylinder where such movement takes place, and this is immediately followed by an explosion in said cylinder which, in its results, is a repetition of the explosion first explained. The mechanism for alternately igniting the charges in the two cylinders, is constructed and arranged to be automatically operated through the medium of a cam, which acts alternately on the opposite extremities of a rocking bar, the opposite ends of said bar carrying liquid which is caused to flow alternately from one cell to the other, the excess of liquid in either cell serving to depress a contact and close the corresponding circuit for igniting the explosive mixture in the corresponding cylinder.

Having briefly outlined my improved construction, I will proceed to describe the same in detail, reference being made to the accompanying drawing, in which is illustrated an embodiment thereof.

In this drawing,—Figure 1 is an elevation partly in section, of my complete duplex internal combustion pump. Fig. 2 is a central vertical section taken through both the cylinders of the pump, the upper part of the pump-conduit construction being also illustrated, and shown on a larger scale than in Fig. 1. Fig. 3 is a fragmentary section illustrating the outer extremity of one of the piston chambers, shown on a still larger scale. Fig. 4 is an end elevation of my improved pump, or a view looking in the direction of arrow 4, Fig. 1.

The same reference characters indicate the same parts in all the views.

Let the numeral 5 designate a suitable foundation or bed, upon which are mounted and made fast two cylinders 6 and 7, which are substantially identical in construction; being suitably spaced for the purpose. Within these chambers are located pistons 8 and 9, which are mounted on the opposite extremities of a stem 10, which consists of two hollow members 12 and 13, whose inner extremities are threaded into the opposite ends of an ellipsoidal connection 14, which is provided with a central cavity 15 having an outlet 16 to the atmosphere. Each of the piston stem members 12 and 13 is open at its inner extremity and communicates with the cavity 15 of the hollow cam or ellipsoidal connection 14; while its opposite extremity is closed by a screw plug 17. Each piston is provided with a number of ports 18 nor-

mally closed by a check valve 19, through the medium of a spiral spring 20, one extremity of which acts on the valve, while the other extremity engages a stop collar 21 threaded on the outer extremity of the stem member. Just outside or beyond the check valve when in its normal position, each piston stem member is provided with one or more perforations 22, through the medium of which the outer compartment 23 of each piston chamber is in communication with the atmosphere by way of the hollow piston stem member, the cavity 15 of the cam 14, and the opening 16 communicating therewith, as heretofore explained.

The inner extremity of each cylinder 6 is provided with a stuffing box 24, through which the corresponding piston stem member passes and whereby a tight joint is formed between the said stem and the opening in the inner head 25 of each cylinder. The outer head 26 of each cylinder is provided with an extension sleeve 27, which is exteriorly threaded to receive a screw cap 28, which, when removed, will give the person in charge access to the check valve extremity of the adjacent cylinder. The extension sleeve 27 forms a cavity 29 which is a continuation of the piston chamber and provides a space into which the outer end of the corresponding piston stem member slightly protrudes. (See the right hand extremity of Fig. 2).

The gasoline or other suitable volatile fluid for supplying the pump may be obtained from any suitable source. As illustrated in the drawing, this fluid is obtained by gravity from a tank 30, which is mounted above the cylinders of the pump and supplied in any suitable manner. Leading downwardly from this tank is a pipe 31, whose lower extremity 32 communicates with a carburetor 33, the latter in turn communicating with a pipe 34 which extends in opposite directions from the carburetor, being composed of two members 35 and 36, each member being equipped with a check valve 37, beyond which is located a spark plug 38 which projects into a small chamber 39 connected by means of a short depending pipe 2 with the inner extremity of the adjacent cylinder. Mounted on a centrally located frame work 40 and suitably spaced, are two pairs of contact members, the said pairs being respectively designated by the numerals 41 and 42. The individual members of one pair are designated by the numerals 3 and 4, while those of the other pair are respectively designated by the numerals 44 and 45. The upper contact of each pair consists of a relatively weak spring, which is normally spaced from the lower contact member, whereby the circuit in which the same is located, is broken. The source of electricity which supplies the cur-

rent of the spark plug circuits, is designated by the numeral 46 (see Fig. 2). From one pole 47 of this source, a conductor 48 leads to a resistance coil 49; while a conductor 50 leads from the opposite pole 51 to the same coil. From this coil leads a conductor 52 to the contact 4, while from the contact 3 a conductor 53 leads to the spark plug 38 mounted on the cylinder 7. A conductor 54 leads from the conductor 52 to the contact 45; while from the contact 44 a conductor 55 leads to the spark plug 38, mounted on the cylinder 6. A conductor 56 leads from the resistance coil 49 to a point 57 on the metal part of the apparatus, whereby the secondary circuit may be said to be grounded, since the entire metal frame work of the structure with the exception of the two pairs of contacts 41 and 42 which are insulated therefrom, is placed in one branch of the circuit, whereby the spark plug circuit may be employed from the point of either plug to the adjacent metal part of the structure, for the purpose of igniting the explosive mixture in the inner extremity of either cylinder, as hereinafter more fully described.

Pivoted connected with the frame work 40 as shown at 58, is a pipe 59, whose opposite extremities are respectively in communication with cells or small chambers 60 and 61, their lower extremities being provided with short downwardly extending pipe members 62 and 63, which connect with the extremities of the pipe 59. Extending downwardly below the extremities of the pipe 59 are projections 64 and 65, whose lower extremities are equipped with anti-frictional rollers 66 and 67. The cells 60 and 61 contain a quantity of liquid and the rollers 66 and 67 are so arranged that they are alternately acted upon by the ellipsoidal cam 14, to tilt the pipe 59 and its connections sufficiently to cause liquid to flow from one cell into the other, the time for this exchange of liquid to take place being so arranged that the quantity in one cell or the other will be sufficient to cause the receiving cell, by virtue of its greater weight and through the medium of a projection 68 with which it is equipped, to press the upper contact 3 or 44, as the case may be, into engagement with its companion contact 4 or 45, whereby the circuit is closed through one of the spark plugs and the explosive mixture ignited in one of the cylinders. Each member of the piston stem is equipped with a stop collar 69, which is adjustable thereon through the medium of a set bolt 70. Each of these stop collars, as it approaches the inner head of the adjacent cylinder, engages a spring 71 forming a buffer or cushion, to prevent the piston of the adjacent cylinder from moving too far toward the outer head of the cylinder. In other

words, this buffer forms a yielding stop to prevent the piston from coming in direct contact with the outer head of the cylinder.

Leading downwardly from the outer extremities of the two cylinders, are pipes 72 and 73, the upper extremity of each of these pipes being in communication with the outer compartments 23 of the cylinders when the pistons are at their outward limit 10 of movement, while the opposite extremities of these pipes communicate as shown at 74, with the upper extremity of an annular chamber 75 formed between the depending inner and outer casings, 76 and 77. The 15 casing 76 includes a central chamber or conduit 78, whose upper extremity is in communication with a tank 79 while its lower extremity, which is exteriorly flared as shown at 80, terminates a short distance 20 above the lower extremity of the casing 77. The lower extremity of this last named casing has an opening 81 adapted to be closed by a check valve 82 vertically slideable on a stem 83, which is threaded into a 25 spider member 84 fitted into the lower extremity of the casing 77. The valve 82 has sufficient vertical movement to permit it to move upwardly, whereby the opening 81 in the bottom of the casing 77 is uncovered to 30 permit the free upward passage of water into the said casing. The lower extremity of the casing 76 is also provided with a perforated spider member 85, whose openings are adapted to be closed by a check 35 valve 86 which is vertically slideable on a stem 87. The casing 77 is secured at its upper extremity to a cap 88, in which the casing 76 closely fits. The lower extremities of the two conduits 72 and 73 are 40 threaded into perforations formed in this cap. An outer perforated casing 89 surrounds the casing 77 and is annularly spaced therefrom as shown at 90. This casing 89 is perforated for the admission 45 of water to the annular chamber 90, surrounding the casing 77, as heretofore explained. These casings 76, 77 and 89, extend downwardly into the body of water 91, constituting the source of supply from 50 which the water is pumped through the medium of my improved apparatus.

Each cylinder is surrounded by a water jacket 92, from the lower part of which a conduit 93 leads to the tank 79. The upper 55 portion of each water jacket is connected by means of a pipe 94 with the corresponding conduit 93. By means of this construction, a circulation of water through the water jacket is maintained during the operation of the pump, whereby the cylinders in which the explosion takes place, are kept cool.

The inner surface of each cylinder is lubricated through the medium of an oil 60 cup 95, having a tubular outlet 96, whose

inner extremity delivers lubricating material of the proper character to each cylinder surface. The movement of the pistons in their respective cylinders serves to distribute this lubricating material.

The operation of my improved construction will be described as follows: Normally, the pistons 8 and 9 of the two cylinders occupy opposite positions therein, that is to say, are located near opposite extremities 75 of their respective cylinders, one piston being at its outward limit of movement of the other at its inward limit of movement. If it be assumed that the piston 8 has just been moved from the inner extremity of the cylinder toward its outer extremity, or the position shown at the right of Fig. 2, while the piston 9 has been simultaneously moved to the position shown in the same figure, a charge of explosive mixture will have been 80 drawn into the cylinder 6 between the piston 8 and the inner head of the cylinder. Simultaneously with the entrance of such charge, the pipe 59 and its connections, has been tilted from the horizontal position to 85 the position shown in Fig. 2, whereby the liquid from the cell 60 or a portion thereof, will flow into the cell 61, the time required for such travel being so arranged as to properly time the closing of the contacts 44 and 90 45, which is accomplished automatically by the pressure of the projection 68 upon the contact member 44, due to the increased weight of the cell 61, resulting from the excess of liquid therein. As soon as this occurs, the circuit in which the right hand spark plug 38 (see Fig. 2) is located, will be closed, and the charge of explosive mixture in the inner compartment of the cylinder 6 95 ignited. The force of this explosion acting 100 through the ports 18 of the piston 8 will move the check valve 19 to the dotted line position (see Fig. 2). The explosive mixture entering the compartment 23, will pass downwardly through the conduit 72, and 105 enter the annular chamber 75 between the casings 76 and 77. This pressure acting on the water in said chamber, will close the check valve 82 and open the valve 86, whereby the water is caused to pass upwardly 110 through the casing 76, and the tank 79, and thence upwardly through a conduit 97 to the desired elevation, it being assumed that the main receptacle to which the water is delivered, is located above 115 the cylinders whereby the water jackets of the cylinders are kept filled, the circulation therein being established through the medium of the pipe connections heretofore explained. It should be stated, that 120 each of the conduits 93 of the circulatory system is equipped with a controlling valve 98. During the movement of the piston 8 toward the right and the movement of the piston 9 in the same direction, air was drawn 125 130

into the chamber of the cylinder 7, simultaneously with the entrance of a charge of explosive mixture to the corresponding chamber of the cylinder 6, the air entering the cylinder 7 by way of the opening 16, the hollow piston stem member 13 and the perforations 22. As the result of the explosion of the mixture within the cylinder 6 as just explained, and the movement of the check valve 19 to the dotted line position, the perforations 22 adjacent the piston 8 were closed, thus preventing any loss to the atmosphere of the pressure produced by this explosion, and causing the entire force of this pressure to be expended upon the water for elevating purposes, as just explained. However, as soon as the force of this explosion has been spent, a partial vacuum exists within the cylinder 6 at the left of the piston 8 (see Fig. 2), with the result that the check valve 19 will move to the position to close the ports 18 of the piston, and open the perforations 22 of the hollow piston stem member 12. Hence, the piston 8 will move toward the left within its cylinder in response to the pull of this partial vacuum, during which time air will enter the cylinder at the right of the piston. The piston 8 will move toward the left to a position fairly near the head of the cylinder, but not close enough to cut off communication between the cylinder and the explosive mixture from the pipe 40, the cylinder head being checked in its inward movement by a cushion between the said head and the piston, there being enough fluid at the left of the piston to form such cushion. During the movement of the piston 8 toward the left, as just explained, the piston 9 will have moved in the same direction within the cylinder 7 with the result that a charge of explosive mixture is drawn into the cylinder 7, at the right of its piston 9. As soon as this occurs, the ellipsoidal cam 14 will have moved toward the left far enough to tilt the rocking pipe 59 and its connections to a position the reverse of that shown in Fig. 2, whereby the liquid from the cell 61 will flow into the cell 60, and cause the spring contact 3 to engage its companion contact 4, and close the circuit through the left hand spark plug 38, whereby the charge of explosive mixture at the right of the piston in the cylinder 7, will be ignited, and the force of this explosion will act through the ports 18 of this piston and the pipe 73, upon the upper surface of the water within the annular chamber 75, with the result that the water is raised to the chamber 78 of the casing 76, as heretofore described. In this manner, explosions occur alternately in the two cylinders and the operation heretofore described is repeated as long as the pump is in operation.

65 In order to prevent back pressure through

the conduits 72 and 73 from the water chamber 75, each of these conduits is provided with a check valve 99 located just above the top of the chamber 75. These check valves open toward the said water chamber, or in the direction of the travel of the explosive force from the outlet compartments 26 of the cylinder chambers.

Having thus described my invention, what I claim is,—

75 1. A pump of the class described, comprising two stationary chambers, pistons located in the respective chambers, a stem to which both pistons are made fast, the pistons dividing their respective chambers into inlet and outlet compartments, the stem being longitudinally movable in the chambers, means outside of the chambers for limiting the movement of the pistons in both directions, each piston having ports, spring-held valves normally closing the said ports in the outlet side, and adapted to open in response to explosions in the inlet compartments, a water-containing chamber in communication with the source of supply, and conduits leading from the outlet compartments of the piston chambers to said water-containing chamber.

80 2. The combination of two piston chambers, pistons therein respectively dividing the chambers into inlet and outlet compartments, the pistons having normally closed check valve-controlled ports adapted to open in response to explosions in the inlet compartments of the chambers, conduits leading from the outlet compartments of the chambers to the water to be raised, a stem to which both pistons are secured, said stem being hollow and forming communication between the outlet compartments of the piston chambers and the atmosphere for exhaust purposes, means for alternately producing explosions in the inlet compartments, and means for maintaining the pistons stationary during such explosions.

85 3. The combination of two chambers, pistons therein respectively dividing the chambers into inlet and outlet compartments, the pistons having ports, spring-held check valves normally closing the said ports on the outlet compartment sides of the pistons and adapted to open in response to the explosions in the inlet compartments of the chambers, a stem to which both pistons are secured, the stem being hollow and open to the atmosphere between the chambers and having perforations in the inlet compartments of the chambers which are open when the piston ports are closed, the piston check valves being adapted to close said perforations when the said ports are open.

90 4. The combination with two chambers, pistons therein respectively dividing the chambers into inlet and outlet compartments, the pistons having ports, spring-held

check valves normally closing the said ports on the outlet compartment sides of the pistons, said valves being adapted to open in response to explosions in the inlet compartments of the chambers, a hollow stem to which both pistons are secured, the said stem being open to the atmosphere beyond the chambers and having perforations in the outlet compartments of the chambers which are open when the piston ports are closed, the piston check valves being slideable on the stem to close said perforations when the piston ports are open, means for alternately producing explosions in the inlet compartments of the chambers, and means for conducting the explosive force from the outlet compartments of the chambers to the water to be raised.

5. The combination of two chambers, pistons therein respectively dividing the chambers into inlet and outlet compartments, the pistons having ports, spring-held check valves normally closing the said ports on the outlet compartment sides of the pistons, said valves being adapted to open in response to explosions in the inlet compartments of the chambers, a hollow stem to which both pistons are secured, the said stem being open to the atmosphere beyond the chambers and having perforations in the outlet compartments of the chambers which are open when the piston ports are closed, the piston check valves being slideable on the stem to close said perforations when the piston ports are open, means for alternately producing explosions in the inlet compartments of the chambers, means for conducting the explosive force from the outlet compartments of the chambers to the water to be raised, and means for holding the pistons stationary during the explosions, the pistons however, being free to travel in response to the partial vacuum produced in the inlet compartment by the explosion.

45. 6. A pump of the class described, comprising two chambers, each having an inlet at one extremity for explosive mixture, and an outlet at the opposite extremity for the escape of the explosive force to the water to be raised, pistons located between the inlet and outlet extremities of the respective chambers and having ports, check valves for normally closing said ports on the outlet sides of the pistons, a piston stem to which the pistons are both secured, the said stem being hollow and serving as a conduit for the escape of the exhaust from the outlet compartments of the chambers to the atmosphere, means actuated by the force of the explosions in the outlet compartments of the chambers for cutting off the exhaust from the outlet compartment of the chamber in which the explosion occurs, during such

explosion, means for alternately producing explosions in the inlet compartments of the two chambers and means for holding the pistons against movement in the direction of the force of the explosion during such explosion, the pistons being, however, free to move in the opposite direction in response to the partial vacuum produced in the inlet compartment of the explosion chamber after the explosion.

7. A pump comprising two chambers, each of which has an inlet for explosive mixture at one extremity, and an outlet for explosive force at its opposite extremity, pistons located in the respective chambers between the inlet and outlet extremities thereof, and having normally closed check valve-controlled ports, means for alternately introducing explosive mixture into the inlet compartments of the two chambers, means for igniting such mixture at properly timed intervals, including two liquid containing cells, a conduit connecting the cells and pivoted for tilting purposes, a stem connecting the two pistons and carrying a cam, the opposite extremities of the conduit carrying lateral projections, and depending projections adapted to be acted on by the cam for tilting purposes, and two pairs of normally separated contacts arranged adjacent the opposite extremities of the said conduit, and adapted to be acted on by the said lateral projections, whereby the cell extremities of the conduit are arranged to alternately bring the pairs of normally separated contacts into engagement for circuit closing purposes.

8. The combination of two piston chambers, pistons therein respectively dividing the chambers into inlet and outlet compartments, the pistons having normally closed check valve-controlled ports adapted to open in response to explosions in the inlet compartments of the chambers, conduits leading from the outlet compartments of the chambers to the water to be raised, a stem to which both pistons are secured, said stem being hollow and forming communication between the outlet compartments of the piston chambers and the atmosphere for exhaust purposes, means for alternately producing explosions in the inlet compartments, and means for maintaining the pistons stationary during such explosions, the pistons however being free to travel in response to the partial vacuum produced in the inlet compartment by the explosions.

In testimony whereof I affix my signature in presence of two witnesses.
